BABY BATHTUB

Egon M. Muller, Hastings on Hudson, N.Y., assignor to
Union Carbide Corporation, a corporation of New
York

Filed Nov. 21, 1962, Ser. No. 72,571

Term of patent 3½ years

(Cl. D4—4)

Fig. 2.

Fig. 1.

Fig. 3.

Fig. 4.

FIG. 1 is a front perspective view of a baby bathtub embodying my new design, the rear being a mirror image thereof;

FIG. 2 is a left side elevational view thereof; and

FIG. 3 is a right side elevational view thereof.

FIG. 4 is a longitudinal cross-section of the tub taken along the axis 4—4 of FIGURE 1.

I claim:

The ornamental design for a baby bathtub, as shown and described.
